STOKER

Eugene L. De Mooy, Cleveland, Ohio, assignor to
Marcella M. De Mooy, Cleveland, Ohio

Continuation of application Serial No. 571,757,
October 29, 1931. This application January 4,
1937, Serial No. 119,051

6 Claims. (Cl. 110—115)

My invention pertains to a stoker and more particularly to a stoker adapted automatically to regulate the periodic supply of crushed coal to a domestic furnace.

5 This application is a continuation of my pending application under like title filed October 29, 1931; Serial No. 571,757.

One object of my invention has been to design a domestic stoker of compact and durable construction, reliable in operation and more economical in manufacture and such objects I have realized by successful operation of my model. Other objects have been to design a hopper agitator with a double movement, as arcuate wave 15 like motion causing periodical heaving of the fuel to frustrate its tendency to pack and to clog the hopper outlet; to crush fuel particles of excessive size and thereafter to project the fuel released from the hopper aided by peculiarly directed air 20 blasts and air inlets ahead of and behind the centrifugal propeller with reference to the direction of fuel delivery; to provide a double adjustment facility in association with a movable frame caster and in association with a shelf for supporting 25 sources of power and to provide a traveling carriage together with means for retaining the carriage in its proper functioning position with reference to the furnace.

Adverting to the drawings:

30 Figure 1 is a side elevation of a stoker embodying my inventions, the same being shown in operative relationship to a standard form of domestic furnace.

Figure 2 is a front elevation of my stoking apparatus.

Figure 3 is a section on line 3—3 of Figure 2 looking in the direction of the indicating arrows, though on a somewhat enlarged scale.

Figure 4 is a section on line 4—4 of Figure 3.

40 Figure 5 is an enlarged vertical longitudinal section, from front to rear, of my stoking apparatus.

Figure 6 is a section on line 6—6 of Figure 5.

Figure 7 is a section on line 7—7 of Figures 45 5 and 10.

Figure 8 is an end view on line 8—8 of Figure 6. Figure 9 is an enlarged top plan view of the hopper, showing parts of the agitating mechanism in alternative dotted line positions.

50 Figure 10 is a section on line 10—10 of Figure 5 looking downwardly.

Figure 11 is a detailed sectional view on line 11—11 of Figure 9.

55 Figure 12 is a side elevation of a modified or portable type of my invention.

Figure 13 is a plan view on line 13—13 of Figure 12.

A floor 1 supports any standard type of domestic furnace 2 which includes grate bars 3 supporting a fuel bed 4. At one side and near its bottom the ash pit is fashioned with an opening 5 the purpose of which will hereinafter appear, and the usual fire door 6 is hinged at 7. For cooperation with my stoker the door 6 is supplied with an opening 8 which is clearly shown in Figure 5.

A sturdy supporting frame includes a fuel delivery chute 9, the flanged mouth of which is bolted at 10 to the margin of the door opening and incidentally clamps a depending flange 11 of a chute-extension member 12 which projects into the fire box as clearly shown in Figure 5.

About on a level with the chute 9 is a peculiarly formed hollow structure 13 which has a horizontally projecting flange or web, bolted at 14 (Figures 1 and 5) to the top of a downwardly extending angle iron support 15, the lower end of which is fashioned as a socket 16 for the reception of a stud 17 adapted to be adjustably secured by means of set screws 18 and also adapted to carry a caster 19 which is movable along the floor 1 to provide an auxiliary support in cooperation with the door hinge 7 upon traveling an arcuate path as prescribed by the swing of the door 6.

30 A shelf 20 shown in Figures 1 to 4 is provided with a forked extension 21 having registering holes 22 for the reception of a dowel pin 23 which is adapted simultaneously to pass through any one of a series of holes 24 which are provided along the lower portion of the support 15. By this means the shelf 20 may be held at any chosen elevation preparatory to tightening it by means of set screws 25.

An electric motor 26 supported on one side of the shelf 20, has its shaft carrying a step pulley 27 and also therebeyond a blower 28 from which a flexible hose 29 leads to the opening 5. A smaller branch hose connection 30 (see Figure 1) communicates through the bottom of the upper end of the chute 9 as shown in Figures 1, 5 and 10.

40 A belt 31 connects the pulley 27 with another step pulley 32 which is fixed to one end (see Figure 6) of a shaft 33 which is mounted in bearings 34 located on opposite sides of an impeller 35 chamber 35. The chamber 35 is located in the lower side of the fuel entry end of the chute 9 and the shaft 33 has keyed to it an impeller 36 provided with vanes 37, the orbital path of the extremities of which intersects the plane of the 55

chute bottom as shown in Figure 5. The opposite end of the shaft 33 carries a worm 38 which meshes with a worm wheel 39 which is fixed to an oblique shaft 40 which is mounted in a bearing 41 and carries at its opposite projecting end a mitre gear 42 which meshes with a conjugate mitre gear 43 on the projecting end of a shaft 44 (Figure 6) which is mounted in bearings 45. The bearings 45 are parallel though elevated 5 with reference to the bearings 34 and both are integral parts of the hollow structure 13. Between the bearings 45 the shaft 44 crosses a hopper-discharge passage which includes cylindrically surfaced side walls 46 as appears in Figure 5, 10 between which rotates a fuel crusher having a plurality of circumferentially projecting vanes 47; the forwardly presented sides of which, with reference to the indicated direction of rotation, are fashioned with projecting lips 48 to simulate 15 a hook-like formation intended to prolong the bite upon a piece of coal. Above the orbital path of the crusher the structure 13 assumes a bowl shape 49 which constitutes the supporting base of a hopper 50 riveted at the plurality of points 20 50a. That side of the interior of the bowl 49 which is approached by a vane 47 when it first commences to descend is fashioned with a projecting abutment 51 (Figure 5) the extremity of 25 which has stepped formation 52 as clearly appears in Figures 5 and 9. As exemplified, the parts 9, 13, 49, 51 and 52 are of integral formation.

The projecting left end (looking toward the furnace) of the shaft 44 has fixed to it a short 30 crank pin 53 as appears to view in Figures 1, 6 and 9. Articulating with the crank pin is one end of an upwardly bent rod 54 the opposite end of which articulates with one end of a rock lever 55 which is pivoted intermediately of its ends at 35 56 to a pedestal 57 on the top of chute 9. Near its two ends, the rock lever 55 is articulated by means of a pair of rods 58 with diametrically opposite sides of an agitating device 59 having the shape of a ring and interiorly hung from the 40 walls of the hopper 50 by a plurality of rods 60 pivotally connected at their ends. As exemplified by the drawings, four rods 60 are employed and their pivotal connections are effected (as best shown in Figure 11) by hooks 61 at their lower 45 ends which engage quadrantly spaced holes in the ring 59 and at their upper ends with inversely bent hooks 62 which are passed through appropriately spaced holes in the hopper 50.

Inviting attention to Figures 5, 7 and 10, the 50 branch air conduit 30 discharges into a distributing chamber 63 formed below the higher end of the bottom of the chute 9 and communicating with two elongated passages 64 which extend along opposite sides respectively of the chute and 55 communicate with the latter each through a plurality of obliquely directed apertures 65. Preferably, the apertures 65 are core or drill holes extending obliquely both toward the furnace opening 8 and toward the bottom of the chute 9 as shown in Figures 5, 7 and 10. Between the crusher 47 and the impeller 37, the structure 13 is provided in horizontal alinement with the chute 9 with a draft hole 66 shown in Figures 2 and 5.

In operation, after closed connection has been 60 made between the furnace door opening and the chute 9, actuation of the motor 26 will simultaneously drive the shafts 33 and 44, the former at a considerably higher speed than the latter, and also operate the blower 28 to force air 65 through the apertures 65. The rotation of the

shaft 44 rocks the lever 55 and accomplishes the peculiar agitating movement within the hopper which is one of the features of my invention. As the suspended ring 59 is alternately given partial turns in opposite directions it must rise obliquely 5 as it is swung whereby it has imparted to it an arcuate wavelike or heaving motion which very successfully breaks down packed fuel not only at the bottom of the hopper, but along its sides. As the fuel with its various sized particles passes 10 into the crusher it is carried around with it and positively conveyed past the projection 51 by the lips 48 on the vanes 47. Any lumps of coal which are of excessive size become crushed between the lips 48 and the stepped abutment 52, the formation of the latter facilitating the required crushing performance by accommodation to lumps of various sizes. After the crushed fuel drops below the crusher the upcoming vanes 37 will steadily 15 project it upwardly into the upper part of chute 9 where the air blasts from the apertures 65 function to accomplish a spray and prolonged flotation of the fuel prior to discharge through the furnace opening 8. The draft opening 66 permits establishment of an air current as indicated by the arrows in Figure 5 and frustrates a clogging effect around the impeller 36. The result is the propulsion through the unrestricted opening 8 of a stream composed of thoroughly 20 comingled fuel and air which unimpeded stream 25 violently intersects the rising volume of the products of combustion in the furnace to there effect a swirling and an eddying whereby a uniform spread of fuel is accomplished, the fuel particles 30 become welded to the fire bed and less fly ash is 35 produced.

I claim:

1. In an over-feed stoker of the class described, the combination of a receiving chamber, means for admitting fuel to said chamber, a rotary impeller mounted therein and provided with projecting blades, a downwardly inclined chute provided with a discharge end and leading from one side of said chamber and adapted to convey crushed fuel propelled by said impeller, said chute being provided on opposite sides with apertures, those on one side converging with respect to those on the other side in the direction of propulsion of said fuel, the side of said chamber opposite to the one from which said chute leads being provided with a draft opening in substantial alinement with the path of propulsion from said impeller, the direction of revolution of said blades being upward past said opening, means for forcing air through said apertures and driving means for said impeller.

2. In an over-feed stoker of the class described, the combination of a receiving chamber, means for admitting fuel to said chamber, an impeller mounted therein, a downwardly inclined chute provided with a discharge end and leading from one side of said chamber and adapted to convey crushed fuel propelled by said impeller, said chute being provided on each of its opposite sides with a series of apertures extending toward the discharge end of the chute, the apertures being directed into the path of propulsion of the fuel, the side of said chamber opposite the one from which said chute leads being provided with a draft opening in substantial alinement with the path of propulsion from said impeller, means for forcing air through said apertures and driving means for said impeller.

3. In an over-feed stoker of the class described,

- the combination of a receiving chamber, means for admitting fuel to said chamber, an impeller mounted therein and provided with projecting blades, a downwardly inclined chute provided 5 with a discharge end and leading from one side of said chamber and adapted to convey crushed fuel propelled by said impeller, said chute being provided on each of its opposite sides with a series of apertures extending toward the discharge end of the chute, the apertures being directed into the path of propulsion of said fuel, the side of said chamber opposite the one from which said chute leads being provided with a draft opening in substantial alinement with the 10 path of centrifugal propulsion from said impeller, the direction of movement of the blades of the impeller being upward past said opening, means for forcing air through said apertures and driving means for said impeller.
- 20 4. In apparatus of the class described, the combination of a fuel-receiving chamber having a draft hole in one of its sides, means for admitting crushed fuel through the upper side of said chamber, a centrifugal propulsion device mounted on a substantially horizontal axis near the bottom of said chamber and having vanes adapted to intercept and to hurl fuel during their upward movement, an elongated chute provided with a discharge end and communicating with another 25 side and at the top of said chamber, said chute being adapted to receive the upwardly hurled fuel and extending toward the furnace door, opposite sides of said chute being provided with air passages having perforations therein, driving 30 means for said device and means for forcing air through said passages and perforations to com-
- pel continued flotation of the fuel as a confined stream along said chute.
5. In a stoker, the combination of a fuel-receiving chamber, means for admitting crushed fuel through the upper side of said chamber, a 5 chute provided with a discharge end and extending laterally from said chamber and communicating with the upper portion of the latter, an air-distributing chamber at the point of connection of said fuel-receiving chamber and chute 10 having air-passages communicating with the chute at its bottom and along its opposite sides, a rotary impeller arranged to turn on a substantially horizontal axis within a lower portion of said fuel-receiving chamber and adapted to have 15 its upwardly moving side intercept admitted fuel and project it into the upper part of said chute, means for driving said impeller and means for forcing air through said air-distributing chamber 20 and through the air-passages to prolong flotation of the fuel along said chute.
6. In a stoker, the combination of a chamber having an inlet and an outlet, means for supplying crushed fuel to said chamber, a fuel-intercepting and flipping device in said chamber and 25 adapted to project intercepted fuel toward the outlet of said chamber, means for actuating said device, said chamber being additionally provided with a draft hole adjacent the orbital path described by an extremity of said device and fluid-projecting means cooperating with said draft hole for premixing air drawn through the latter with the projected fuel and for prolonging flotation of the flipped fuel during its violent projection through the outlet of said chamber. 30 35

EUGENE L. DE MOOY.
